GEORGE S. SOWERS, OF SPRING HILL, KANSAS.

SUPPORTING MEANS FOR HAY-SLINGS.

1,398,472.

Specification of Letters Patent. Patented Nov. 29, 1921.

Application filed January 28, 1919. Serial No. 273,668.

To all whom it may concern:

Be it known that I, GEORGE S. SOWERS, a citizen of the United States, residing at Spring Hill, in the county of Johnson, State 5 of Kansas, have invented a certain new and useful Improvement in Supporting Means for Hay-Slings, of which the following is a full and exact specification.

This invention relates to hay rack improvements, and aims to provide an improved rack construction in which provision is made for carrying and retaining the hay slings during the times when these slings are not in actual use.

10 For this purpose I have devised a novel form of supporting means for the hay slings in conjunction with the uprights at one end of the rack, and so arrange this supporting means for carrying the hay slings and retaining the same on the exterior of the uprights or outside the rack until the workman is ready to use the slings in the process of building up the load on the rack, whereby 15 the slings are conveniently carried and kept 20 out of the way of the loading operation, and yet may be readily and quickly taken off the supporting means one at a time as fast as they are needed.

It is also an object to provide a convenient 25 form of folding supporting means of the character described, and adapted to be swung out of operative or supporting position and so retained without any disadvantages attending the presence of such supporting means as a part of the rack.

With this general object in view, the invention will now be described with reference to the accompanying drawing illustrating a 30 rack construction with one form of embodiment of supporting means for the hay slings, after which the novel features therein will be defined and set forth in the appended 35 claim.

In the drawing—
40 Figure 1 is a side elevation showing a hay rack provided with a hay sling supporting means embodying the present feature of the improvement;

Fig. 2 is a front end view of the same; 45 Fig. 3 is an enlarged sectional detail view showing a portion of one end of the rack, with one of the hay sling supporting members appearing in side elevation and in operative position;

50 Fig. 4 is a similar view with the hay sling

supporting member shown in folded or inoperative position; and

Fig. 5 is a rear edge view of one of said supporting members.

Referring now to the drawing in detail, 60 this illustrates a wagon 6 supporting a hay rack comprising the rack bed 8 and the end uprights 10, 12, at the front and rear, respectively, of the bed 8. The corner uprights 10 and 12 are shown as provided with 65 retaining pockets 14 for removably receiving the side bars 16 which, when not in use, are nested in the pockets 18 on the rack bed, all as set forth in my copending application Serial No. 239,280, filed June 10, 1918, and 70 therefore forming no part of the present invention.

For supporting the hay slings 20, a pair of the uprights, preferably two of the intermediate uprights 10 at the front of the rack 75 (since the hay is commonly loaded over the rear end) are provided with foldable supporting devices, each of which comprises an arm 22 pivotally supported by means of a pin 24 in the outer end of a bracket plate 26 80 secured to the upright by bolts 28. The bracket plates 26 are fastened in inclined position, with their outer ends projecting past the outside edges of the uprights, as shown in Figs. 3 and 4, and each arm 22 is 85 provided with a stop lug 30 adapted to engage the under edge of the outer projecting end of the corresponding bracket plate 26, whenever the arm is swung outward into operative or supporting position (see Fig. 90

3). In this way, the arms 22, when swung outward, are presented in upwardly inclined position adapted to receive and support the hay slings 20 by engagement with the rigid transverse members 32 of said slings. This 95 construction also permits the arms 22 to be swung upward into approximately vertical position, in which position the same may be secured in any convenient manner, as by means of cords or wires 34, to the top cross-piece 36, as illustrated in Fig. 4. The outer ends of the arms 22 may be formed with suitable openings 38 for receiving said cords or wires 34.

It is thus apparent that a simple and convenient supporting structure is provided for carrying out the desired object of the invention. Hay slings are an efficient means for hay loading and unloading purposes, even more so, in the judgment of many, than the 110

well known hay-fork device, because of the danger of personal injury which attends the use of the same, and the damage which is often done to the rack and also to the barn structure in lifting unduly heavy loads, it being difficult to always properly gage the load for which the fork is set. I believe, however, that the hay slings have not met with the wide-spread use which they deserve because of the fact that no convenient supporting means has heretofore been provided, so far as I am aware, in conjunction with the rack for carrying the slings in a proper and efficient manner and avoiding the necessity of the workman getting on and off the load as often as a sling is needed to be inserted in place in the load. For overcoming this defect, therefore, the present improved device provides a means for carrying the slings in a position convenient to be used and for keeping them out of the way until their use is needed in the loading operation, and likewise providing a place for storing them between loads, or as the rack is being unloaded. The use of the improved construction is clearly illustrated in Fig. 1. The front uprights of the rack are selected for mounting the supporting devices because the hay is commonly loaded over the rear end by the usual type of hay-loader 40. As the load is built up the slings 20 are removed from the supporting arms 22, one by one, and placed at intervals through the load. The position of the supporting arms thus keeps the slings entirely out of the way, so that neither the arms 22 themselves nor the slings 20 supported thereby interfere in any way whatsoever with the loading operation, and the slings are at all times maintained in the handiest possible position for enabling the workman to take hold of the slings as soon as they are needed. When the rack is not being used for hay loading purposes in the manner described,

the arms 22 may be folded up into approximately vertical position as shown in Fig. 4, and secured in this inoperative position as indicated, where they are practically out of the way and offer no interference with any other desired use of the rack, or, if a tarpaulin covering, for example, is to be let down over the load, this approximately vertical position of the arms 22 allows this to be done without obstructing such operation in any way. If preferred, however, the arms and bracket plates may be entirely removed from the rack, when their use may not be desired for a considerable period of time, by simply removing the bolts 28.

Having described the invention, what I claim as new and desire to secure by Letters-Patent is:

Means for carrying hay slings on the outside of hay racks comprising, in combination, a rack bed having spaced uprights at one end of the bed, and folding hay sling supporting members carried by said upright members, said supporting members comprising bracket plates secured in inclined position to said upright members near the upper ends thereof and supporting arms pivoted to said bracket plates to swing outward from approximately vertical into alignment with said bracket plates for supporting the hay slings on the exterior side of said upright members, the upper ends of said arms extending flush with the upper ends of said upright members when said arms are in their approximately vertical position, said arms being also provided with stop lugs adapted to engage the lower edges of said bracket plates for maintaining said arms in upwardly inclined position when in their operative or sling-supporting position.

In witness whereof I hereto affix my signature.

GEORGE S. SOWERS.
